UNITED STATES PATENT OFFICE.

EUGENE V. MYERS, OF EAST ORANGE, NEW JERSEY, ASSIGNOR TO A. SCHRADER'S SON, INCORPORATED, OF BROOKLYN, NEW YORK, A CORPORATION OF NEW YORK.

TIRE-VALVE OR THE LIKE.

1,367,826.

Specification of Letters Patent.

Patented Feb. 8, 1921.

Application filed May 6, 1915. Serial No. 28,191.

To all whom it may concern:

Be it known that I, EUGENE V. MYERS, a citizen of the United States of America, residing in East Orange, in the county of Essex, sex and State of New Jersey, have invented certain new and useful Improvements in Tire-Valves or the like, of which the following is a specification.

This invention relates to tire valves or the like, and aims to provide certain improvements therein.

There are certain advantages in that type of valve, in which the valve seat, valve proper and actuating spring (if one is present) are contained in a casing which is coupled to the valve shell. Numerous instances of this are shown in prior patents, but in such prior constructions the casing has been formed as a continuation of the shell, adapted to fit only partially within the latter, and has always carried the nipple of the shell. In such constructions the pump coupling screws on to the casing and not on to the valve shell. The screwing and unscrewing of the pump coupling has a tendency to loosen the connection of the casing with the shell and renders impractical the use of a plain screwthread. Some form of non-rotative connection has hence been adopted in connection with a union for coupling the two parts together. According to the present invention a casing is provided which is adapted to fit wholly or partially within the shell in such manner that the nipple may be formed as a part of the shell instead of being carried by the casing. This permits the pump coupling to be screwed directly on the shell. Furthermore in the usual construction of valve insides, a seat member is provided which is swiveled to a screwthreaded plug for holding it in place. The seat member is provided with a packing which engages a tapered shoulder on the interior of the valve shell. This construction demands a considerable constriction of the effective passage through the seat member. According to the present invention in its preferred form, the bore in the shell is a plain bore for the most part of its length, and the casing is preferably screwthreaded near its lower end, while the packing is preferably arranged below the screwthreaded portion. This permits the enlargement of the valve around its seat, so that greater areas for the passage of air can be obtained.

The invention comprises other improvements which will be more fully pointed out.

Referring to the drawings which illustrate one form of the invention,—

Figure 1 is a diametrical section of the top 60 of a valve embodying the present invention;

Fig. 2 is a side elevation of the valve casing detached;

Fig. 3 is a cross-section on the line 3—3 in Fig. 1; 65

Fig. 4 is a side elevation of the valve proper.

Referring to the drawings, let A indicate a valve shell adapted to be secured to a pneumatic tire, and B one form of casing 70 provided by the invention.

The casing B is intended to practically inclose the valve proper C and the spring D, if used. Preferably the casing is formed with a seat E near its top. The casing may 75 be variously constructed, but is shown as formed in two parts F and G, the lower of which, G, is adapted to fit in the upper, F. The wall of the part F is preferably made as thin as is consistent with the necessary 80 strength so as to provide as large a valve chamber H as possible. The lower part G may have passages of smaller diameter, since there is little or nothing to restrict the flow of air through such part. Preferably 85 a socket I is formed in the lower part to provide a seat for the spring D. The part G is also preferably provided with an annular groove J adapted to receive a packing K which makes a tight joint with the interior of the valve shell, as for instance with a tapered shoulder or seat L. The shoulder L is preferably located a distance below the top of the valve shell which is greater than the length of the casing, so that when the 95 casing is seated in said shell, its top will lie below the top of the valve shell. A screw-thread M is formed on the casing B, preferably above the packing, such screwthread 100 engaging a similar thread N on the interior of the valve shell. If desired the threaded parts may be at the upper end of the casing, but it is preferred that they occupy the positions shown. The lower part G and upper part F may be connected in any suitable 105 way, as by driving one into the other, or otherwise.

The valve proper C may also be variously constructed but is preferably formed as shown. As illustrated, it comprises a cylinder 110

drical member having an internal socket O adapted to receive the top of the spring D, a packing socket P adapted to receive the washer Q, and a pin R to be used for deflating purposes. Guiding wings such as S are preferably formed on the outer side of the valve proper so as to guide the valve while allowing passages T T around the valve, as best shown in Fig. 3.

10 The casing B in the form shown is adapted to fit entirely within the valve shell, but its upper end may project therefrom if desired so long as the nipple U of the valve shell is retained so as to be capable of co-operating with a pump or the like. It is preferred, however, to form the casing so that it is substantially entirely inclosed, thus leaving the upper edge V of the nipple exposed to form a seat for the cap packing, 15 such as W, whereby any leakage through the valve either around the casing or past the valve proper is caught by the cap.

The outer diameter of the nipple U is substantially fixed in practice. In the usual 20 construction of valve the interior of the nipple is reduced in diameter by a screw-thread, which is necessary for the usual type of valve insides. By the present invention this screwthread may be omitted and the increased 25 diameter utilized. Furthermore in the usual construction the space is further restricted by the fact that a swivel connection must be made between the seat member and its retaining plug. According to the preferred form of the present invention this 30 additional space becomes available for the passage of air. The reduction of the diameter of the seat may also be increased on account of the fact that the packing is preferably 35 arranged at the lower part of the casing where more space is available, on account of the fact that there is no constriction at this point due to the valve pin.

While I have described and claimed one 40 form of the invention, it will be understood that I do not wish to be limited thereto, since various changes may be made therein without departing from the spirit of the invention.

50 I claim as my invention:—

1. In a tire valve or the like, the combination of a casing adapted to be substantially entirely inclosed within a valve stem and having an internal valve seat, an internal valve chamber and an internal valve plunger, and a packing for said casing located below the valve seat.

2. In a tire valve or the like, the combination of a casing adapted to be substantially entirely inclosed within a valve stem and having an internal valve seat, an internal valve chamber and an internal valve plunger, said casing having cylindrical external walls at the point of the valve seat, and a 65 screw-thread below said wall.

3. In a tire valve or the like, the combination of a casing adapted to be substantially entirely inclosed within a valve stem and having an internal valve seat, an internal valve chamber and an internal valve plunger, 70 said casing having cylindrical external walls at the point of the valve seat, a screw-thread below said wall, and a packing below said screw-thread.

4. The combination of a valve shell having 75 a chamber adapted to receive a valve casing, a shoulder in said shell, with a valve casing having a valve seat and a valve proper, and a packing at its lower end adapted to make a tight joint with said shoulder, said valve casing being adapted to be received entirely within the chamber, and said shoulder being located a distance below the top of the valve shell which is greater than the length of the casing. 85

5. In a tire valve or the like, the combination with a valve shell adapted to be connected with the tire tube, said valve shell having a screw-threaded nipple at its outer end adapted for connection to a pump 90 coupling, and a valve casing having its inner end fitting within said shell, said valve casing being of less diameter throughout than the bore of said nipple, whereby it does not interfere with the application of such 95 pump coupling, a packing adapted to make a tight joint between said valve casing and said shell, said packing being arranged at the lower end of said valve casing, said valve casing having a valve chamber within it, a 100 seat within said chamber located above said packing and a valve proper within said chamber, said valve proper at all times movable to and from said seat.

6. In a tire valve or the like, the combination with a valve shell adapted to be connected with the tire tube, said valve shell having a screw-threaded nipple at its outer end adapted for connection to a pump coupling, and a valve casing having its inner end 110 fitting within said shell, said valve casing being of less diameter throughout than the bore of said nipple, whereby it does not interfere with the application of such pump coupling, a packing adapted to make a tight 115 joint between said valve casing and said shell, said packing being arranged at the lower end of said valve casing, said valve casing having a valve chamber within it, a seat within said chamber located above said 120 packing and a valve proper within said chamber, and a spring within said valve chamber adapted to press said valve proper against its seat to close the same.

7. In a tire valve or the like, the combination with a valve shell adapted to be connected with a tire tube of a valve casing fitting entirely within said shell, whereby it does not interfere with the application of a pump coupling to said shell, a packing at 125 130

- the lower end of said valve casing adapted to make a tight joint between said valve casing and said shell, said valve casing having a valve chamber within it, a seat within 5 said chamber located above said packing, and a valve proper within said chamber.
8. In a tire valve or the like, the combination with a valve shell adapted to be connected with a tire tube of a valve casing fitting entirely within said shell, whereby it does not interfere with the application of a pump coupling to said shell, a packing at the lower end of said valve casing adapted to make a tight joint between said valve 10
- casing and said shell, said valve casing having a valve chamber within it, a seat within said chamber located above said packing, a valve proper within said chamber, and a spring for pressing said valve proper toward said seat. 15
- In witness whereof, I have hereunto signed my name in the presence of two subscribing witnesses. 20

EUGENE V. MYERS.
